ABSTRACT OF THE DISCLOSURE

A punch press is provided with a releasable guide assembly in the form of a yoke adjacent to its ram, within which there are reciprocable stripping means that slidably guide a toolholder normally supported by the ram. On detachment of the guide assembly from the press which releases the toolholder from the ram, a pair of pivotable levers automatically move into a position where they jointly temporarily support the toolholder while a punch tip portion is replaced. Release of the levers is automatic in response to resecuring the guide assembly.

Background of the invention

Field of the invention.—This invention pertains to structure for automatically supporting a toolholder when the same is temporarily disconnected from a supporting ram during a tool change.

Description of the prior art.—In Patent No. 3,270,605 owned by the assignee of this invention there is shown a guide assembly, and there is also shown structure for fixedly securing the guide assembly to a stationary portion of the press. On release of the clamping mechanisms therein disclosed and claimed, the toolholder or guide assembly can be moved out of its normal operating position to enable manual access to the tooling carried therein for the purpose of effecting a tool change. In that device, the punching structure is supported by the guide assembly, and the ram has nothing supported by it. This arrangement is entirely satisfactory for punch elements up to a certain size, as sufficient stripping energy can be stored conveniently in springs. However, where the maximum tool size has been increased considerably, a different stripping arrangement has been necessitated which entailed a T-slot arrangement by which the punch element was indirectly supported by the ram. When such an arrangement has been combined with the releasable guide assembly of the type shown in Patent No. 3,270,605, a problem has arisen as to how to support the tooling when the guide assembly has been detached from the ram, such problem being heightened by the fact that the tooling is of considerable weight, and is subject to damage in the event that it is inadvertently dropped.

Summary

In accordance with the present invention, we have provided in the disclosed embodiment a pair of pivotable levers which are normally pivoted to a retracted position because of the influence of an abutment on the press, and which automatically pivot to a position where they jointly support the toolholder whenever the guide assembly is moved out of its normal supported position, such movement simultaneously disconnecting the toolholder from the ram. On restoration of the toolholder and the guide assembly to their operating position where they are again secured, the supporting means automatically release the toolholder, freeing it for reciprocation in response to the movement of the ram.

Accordingly, it is an object of the present invention to provide tool support structure which automatically supports tooling at such time as the tooling is released from its normal support.

2

Another object of the present invention is to provide supporting means for tooling which means are responsive to the release and the securement of the structure that supports the tooling so as to have a temporarily opposite effect.

A further object of the present invention is to provide a safety mechanism to preclude inadvertent release of the temporary supporting means.

Many other advantages, features and additional objects of the present invention will become a manifest to those versed in the art upon making reference to the detailed description and to the accompanying sheet of drawings in which a preferred structural embodiment incorporating the principles of the present invention is shown by way of illustrative example.

On the drawings:

FIG. 1 is a side cross-sectional view of tool support structure provided in accordance with the principles of the present invention; and

FIG. 2 is an enlarged fragmentary top plan view of a portion of FIG. 1, FIG. 1 being taken generally along the line I—I of FIG. 2.

As shown on the drawings:

The principles of this invention are particularly useful when embodied in a tool support structure such as illustrated in FIG. 1, generally indicated by the numeral 10. The tool support structure 10 is provided for use with a press, such as a punch press having a reciprocable ram 11 and a portion 12 which for purposes of this invention comprises an abutment. The press includes conventional stationary portions (not shown) adjacent to the ram, of the type described in the above-mentioned patent to which a guide assembly 13 is releasably secured, such as by means shown in said patent. The left side of FIG. 1 represents the front of the machine which would be facing toward the operator, and in accordance with such prior patent, the guide assembly 13 has an arm extending toward the viewer that has been removed because of sectioning, and a rearwardly extending arm obscured by the illustrated structure which jointly comprise a yoke of a known type. When such yoke or guide assembly 13 is released, the guide assembly 13 is free to be moved horizontally to the left away from the abutment 12, and away from the ram 11, out of all engagement therewith. To restore the press to operating condition, the guide assembly is moved to the right to the position drawn where the same is secured in operating position by the known clamping means identified above.

The guide assembly 13 includes a bushing 14 which is held in a fixed position in a conventional manner, and which defines a first aperture 15. The aperture 15 receives and slidably guides the lower portion of stripping means 16 for reciprocation, the stripping means 16 having a suitable keying means 17 to preclude rotation between such stripping means and the bushing 14. The stripping means 16 has a second aperture 18 which is concentric with the first aperture 15. The second aperture slidably receives a toolholder 19. Suitable keying 20 is provided between the toolholder 19 and the stripping means 16 to preclude relative angular rotation. The upper end of the toolholder 19 is connected to the ram 11 by means of a T-slot and T-head connection, in this embodiment, the T-head 21 being a part of the toolholder 19, and the T-slot being a part of the ram 11 and extending in a front to rear direction. The toolholder 19 has a continuous circumferential groove 22 which defines and provides a downwardly directed shoulder 23 lying in a horizontal plane and being convex as viewed from the side.

The stripping means 16 includes a stripping sleeve 24 which carries the keying 17 and which has an internal keyway for the keying 20. At its lower end, the stripping sleeve 16 supports a stripping plate 25 as by a snap ring

26, the stripping plate 25 being here illustrated with a maximum diameter to coat with a maximum diameter punch tip 27 supported by the toolholder 19. The stripping sleeve 24 has a flange 28 at its upper end which is trapped by a snap ring 29 in a downwardly facing recess provided in a stripping collar 30. The stripping collar is generally circular, but has a forward ear 31 and a rearward ear 32. A set of four lifter springs 33 acts between the guide assembly 13 and the stripping collar 30, while a set of four lifter spring bolts 34 acts between the stripping collar 30 and the guide assembly 13 to place a preload on the lifter springs 33 of such magnitude as to insure that the stripping collar 30 will take a normal rest position as illustrated.

As a matter of interest, and not forming a part of this invention, the abutment 12 acts on the rear ear 32, and a similar component 35 acts through an ear extension 36 on the forward ear 31 of the stripping collar 30 to hold the stripping plate 25 in firm engagement with the workpiece during punching and stripping. The structure described enables the bushing 14, the stripping sleeve 16, the toolholder 19, and including the head 21 and the punch tip 27 to be rotated to any selected angular position so that where the punch tip 27 is non-circular, its shape may be oriented properly in an angular manner with respect to the workpiece.

Considering only the structure thus far described, if the guide assembly 13 were shifted to the left, such that the toolholder head 21 could disengage from the ram 11, the toolholder 19 and the punch tip 27 would fall through and drop out at the bottom of the guide assembly 13. Such a property is necessary to enable the ram 11 to reciprocate the toolholder 19 with its tool bit 27.

In accordance with another of our inventions, the toolholder 19 has a manual actuator 37 which is rendered accessible to the operator when the toolholder 19 has been moved to the left out of engagement with the ram 11. To understand the present invention, it is sufficient to explain that manual movement of the manual actuator 37 will release the punch tip 27 from the toolholder 19, so as to permit it to drop, such as into the palm of the operator. Such condition enables the operator to replace the punch bit 27 with a further selected punch tip. Normally, the operator will also replace the stripping plate 25 by removal of the snap ring 26 which has ears (not shown) facilitating such replacement.

In accordance with the present invention, supporting means generally indicated at 38 are provided, which can best be seen in FIG. 2. The supporting means 38 includes at least one and preferably two pivotable levers 39, 40, respectively secured pivotably as by a pair of screws 41, 42 which extend into the stripping collar 30 of the stripping means 16. The lever 40 is substantially a mirror image of the lever 39, and the levers 39, 40 are disposed on the opposite sides of, namely to the left of and to the right of the axis of the apertures 15, 18 as viewed by the operator. Each of the levers 39, 40 has a concave knife-like portion 43 and a concave cam surface 44. A spring 45 connects the levers 39, 40 for biasing the knife-like portions 43 toward each other and hence toward the groove 22 with which they are aligned. As the guide assembly 13 is withdrawn to the left, all of the structure illustrated in FIG. 2 moves to the left except for the abutment 12. As such movement begins, the ends 46 of the cam surfaces 44 are cammed apart aided by the spring 45 to enable the knife edges 43 to move into the groove 22 where the upper surface of the knife edges 43 may engage the downwardly directed shoulder 23 before the toolholder head 21 is fully disengaged from the ram 11. In this first position the lever or levers 39, 40 temporarily retain the toolholder 19 against dropping out to enable the operator to make a selected change in choice of punch bit 27. On completion of such change, return of the structure shown in FIG. 2 toward the abutment 12 causes the abutment 12 to be engaged by a pair of ears 47 which form the inner end of the cam surfaces 44 whereby the levers 39, 40 are 70 75

gradually drawn to the position shown in FIG. 2 wherein the ear portions 47 act against the abutment 12 against the force of the spring 45 to hold the levers 39, 40 in the second or retracted position wherein they are spaced from the toolholder 19. The illustrated position is thus the normal operating position wherein the cam surface 44 is engaged by the convex portion of the abutment 12 on the press.

Considering the supporting means 38 thus far described, when the guide assembly 13 has been shifted to the left and the supporting means 38 are holding the toolholder 19, it is possible due to an inadvertence, such as carelessness, to manually grasp the rearwardly directed ears 46, 46 and to move them together, thereby effecting release of the toolholder 19 which would then drop through the guide assembly 13. The location of the supporting means 38 at the rearward part of the stripping means 16 is intended to render the supporting means 38 less accessible, and hence less likely to be subject to such inadvertence. If only one of the levers 39, 40 is manually or otherwise moved to the illustrated position when it should be in the toolholder supporting position, the other lever will hold the toolholder 19 by itself.

In the event that the user should desire a safety mechanism to preclude against such inadvertence, we have provided an optional resiliently biased pin 48 illustrated in FIG. 1 in a retracted position. The pin 48 has a laterally projecting cam portion 49 having a ramp 50, the cam portion 49 being disposed beneath a generally horizontal portion of the abutment 12 and normally urged against it by a spring 51 which provides such resilient bias. As the guide assembly 13 is shifted to the left as explained, the ramp 50 enables the pin 48 to rise and to move into a position adjacent the levers 39, 40 after they have entered the groove 22, making it impossible to grasp the ears 46 and to draw them together by an amount sufficient to release the knife-edge portions 43 from the groove 22. On movement of the guide assembly 13 to the right as previously explained, the ramp 50 engages the abutment 12 to retract the pin 48 prior to the time that the abutment 12 reactively cams levers 39, 40 out of the groove 22.

As the levers 39, 40 are of substantially the same thickness and are supported on the same surface, the cam portions 44, together with the ears 47 and 46 are oppositely cut away as best seen in FIG. 1 to enable the overlap illustrated in FIG. 2. As the guide assembly 13 is absolutely fixed during punching, the heads of the screws 34 are likewise also fixed, whereas the stripping mechanism 16 moves downwardly. To preclude interference between the levers 39, 40 and the rearward lifter spring screws 34 during punching, suitable cutouts are provided as shown in FIG. 2 to provide clearance.

Although various minor modifications might be suggested by those versed in the art, it should be understood that we wish to embody within the scope of the patent warranted hereon all such embodiments as reasonably and properly come within the scope of our contribution to the art.

We claim as our invention:

1. A tool support structure for a press having a ram, comprising:
  - (a) a guide assembly arranged to be releasably fixedly secured to a stationary portion of the press and having a first aperture;
  - (b) stripping means reciprocably supported in said first aperture and having a second aperture concentric with said first aperture;
  - (c) a toolholder disposed in said second aperture and normally releasably supported by the ram and reciprocated by said ram; and
  - (d) means movably carried by said stripping means and disposed in a non-supporting relation to said toolholder whenever said toolholder is aligned with said ram, and movable to a position for supporting

said toolholder when said guide assembly and said toolholder are released from their supports.

2. A tool support structure according to claim 1, which includes lifter spring means acting between said guide assembly and said stripping means and having a combined preload greater than the combined weight of said stripping means and said supporting means for insuring vertical registration between said supporting means and said toolholder.

3. A tool support structure according to claim 1, in which said tool holder has a downwardly facing shoulder, and in which said supporting means comprises a pivotable lever movable to a first position in which a portion of said lever extends beneath said shoulder and is engaged thereby and to a second position where said lever portion is spaced from said toolholder.

4. A tool support structure according to claim 3, in which said lever has a cam surface normally engaged by an abutment on the press for holding said lever in said second position, and a spring for moving said lever to said first position in response to movement of said cam surface away from the abutment as said guide assembly is released from its support.

5. A tool support structure according to claim 4, in which said cam surface is concave for cooperation with a convex surface on the abutment.

6. A tool support structure according to claim 3 in which said shoulder by which said toolholder is supported in convex and said lever portion is concave.

7. A tool support structure according to claim 3, in 30 which said shoulder is defined by a continuous circumferential groove in said toolholder for enabling said lever to enter and coact therewith at every angular position of said toolholder.

8. A tool support structure according to claim 3, in 35 which said supporting means comprises a second pivotable

lever engageable by said toolholder and which is substantially a mirror image of said first named lever, said levers being disposed on opposite sides of the center of said apertures.

5 9. A tool support structure according to claim 8, in which a spring connects said levers and urges them toward said first position, and in which each of said levers has a cam surface normally jointly engaged by an abutment on the press for holding said levers in said second position.

10 10. A tool support structure according to claim 3 which includes a resiliently biased pin having a laterally projecting cam portion for being normally engaged by a generally horizontal portion of the abutment on the press for being held thereby in a retracted position, said pin being movable by said spring to an extended position adjacent to said lever in response to release of said guide assembly from its support for precluding movement of said lever out of said first position.

15 11. A tool support structure according to claim 10 in which said cam portion has a ramp for engaging the horizontal portion of the abutment to move to said retracted position in response to movement of said guide assembly to its operating position.
